UNITED STATES PATENT OFFICE.

EDGAR E. BUNKER, OF DUBUQUE, IOWA.

FIRE-BOX LINING.

SPECIFICATION forming part of Letters Patent No. 274,169, dated March 20, 1883.

Application filed July 19, 1882. (No model.)

To all whom it may concern:

Be it known that I, EDGAR E. BUNKER, of Dubuque, in the county of Dubuque and State of Iowa, have invented a new and useful Improvement in Fire-Box Linings; and I do hereby declare that the following is a full and exact description of the same, reference being had to the accompanying drawings, and to the letters of reference marked thereon.

10 The object of the invention involved in the subject-matter of this application is to produce a simple adjustable fire-box lining for fire-boxes, which can readily be vertically and longitudinally adjusted for its application to cooking-stoves having fire-boxes of different heights and lengths without the aid of the commonly-used bolts and slots and lugs or keys, &c.; and the invention therein consists in providing the fire-box lining proper and each of the adjustable and removable wings thereof with a series of grooves or corrugations and correspondingly-shaped ridges suitably arranged to engage with each other, and thereby render the fire-box lining capable of adjustment to any required height and length; and it further consists in the construction, arrangement, and combination of the parts composing it, as will be fully hereinafter set forth, and pointed out in the claims.

30 In order that a thorough understanding may be had of the invention, and to enable those skilled in its relative art to know how to construct and properly adjust and apply the same, I will proceed to describe it with reference to the accompanying drawings, in which—

Figure 1 is a plan view of the rear side of a fire-box lining constructed in accordance with my invention; Fig. 2, a similar view of the body of the fire-box lining and under side of the adjustable lower wing detached therefrom; Fig. 3, a view in detail of one of the adjustable side or end wings, and Fig. 4 is a section of the body taken on the line xx of Fig. 2.

Like letters of reference indicate corresponding parts in each figure of the drawings.

A represents the body of the fire-box lining, cast on its rear side, as shown, with a series of V-shaped grooves or corrugations, a , and having the usual rearwardly-curved upper edge, which extends partly over the oven. This body is further provided on its rear side and along the entire length of its lower edge with a

depression, B, having near each end thereof an upward extension, B', terminating near the base of the curved upper edge, and in each of which extensions, near its point of connection with the portion B, is located a ridge, b , of a shape and size corresponding with grooves or corrugations cut in an arm on each end of an adjustable wing, C, now to be described. The depression B, with its extensions B', above described, is made of a sufficient width and depth to receive a correspondingly-shaped wing, C, adapted to be adjustably attached to the lower edge of the fire-box lining, and is, as shown in Fig. 2, provided near each end with an arm, C', extending upwardly therefrom, and provided on its under surface with a series of V-shaped grooves or corrugations, c , any one of which is adapted to fit nicely over the ridge b in the depression on the body of the fire-box lining, and thereby enable the said wing to be vertically adjusted and attached thereto, accordingly as required.

On the rear side of the body A, and at each end of the series of grooves or corrugations a , is cast a hook, D, under which the arms of the adjustable side or end wings (presently to be described) are placed and held against the body of the fire-box lining. Directly under each of these hooks D a rectangular opening, d , is cut entirely through the fire-box lining, for the purpose of avoiding cores in casting, and inasmuch as they are completely covered by the arms of the end wings when applied to the fire-box lining, they afford no entrance whatever for ashes into the air-chamber.

E E represent the adjustable side or end wings, of a width corresponding with that of the body of the fire-box lining, (when extended to its greatest possible limit,) and capable of being accordingly lessened in width by means of breaking-grooves e , arranged upon the under surface of each near its lower edge, as shown in Fig. 3. Each of these wings is provided, as shown, with an arm, F, cast therewith, and extending outwardly from its center at right angles thereto. Upon the under side or contact-surface of each wing, and at the extreme end of its arm F, is located a ridge, f , as shown, which, when the wings are applied to the ends of the body A of the fire-box lining, engages with one of the series of V-shaped grooves or corrugations a , by means of which and the hooks D

(under which the arms pass, as before mentioned) the said wings can be lengthwise adjusted, as desired, and held in the position given them.

5 It will be obvious that instead of attaching the wing C to the lower edge of the body of the fire-box lining, it could be equally as well adapted for attachment to the upper edge thereof by merely reversing the location of the 10 depression B, and accordingly changing that of the ridge b in the extensions B' of said depression. If it be desired to make this change, the rearwardly-curved upper edge of the body of the fire-box lining would necessarily have 15 to be removed and made to form a part of and hold a like position on the wing C.

It will further be apparent that instead of casting each of the side or end wings in one piece, with breaking-grooves on the lower edge, 20 they could be composed each of two sections, and adapted by grooves or corrugations and ridges to fit nicely together, and be of a shape like that shown in Fig. 3, and capable of adjustment in width to correspond with that of 25 the body of the fire-box lining. Although this form of construction will answer all practical purposes, it will be found objectionable, from the fact that the two sections composing the wing are required to be of too light a weight 30 to cast well, and the other form will therefore prove the more efficient in practice.

The corrugations and ridges, instead of being located on their respective parts, as herein described, may be correspondingly reversed without 35 producing any change in the manner of adjusting and attaching such parts to the fire-box lining.

It will be understood that the adjustable lower wing, C, is only provided in order to supply the trade with "backs" capable of fitting the few deep fire-boxes in use, while for boxes of the ordinary sizes of stoves its employment can conveniently be done away with and the fire-box lining proper cast plain and thin, with 40 breaking-grooves on its lower edge, and of a width sufficient to be accommodated in the largest of the ordinary-sized fire-boxes.

From the foregoing description it will be seen that the entire fire-box lining is of a simple and cheap construction, each of its component parts being cast separate from the other,

complete in itself, and adapted to be adjusted and secured together and applied to fit fire-boxes of various depths and lengths without the aid of bolts or other similar locking devices 55 usually employed.

Having thus described my invention, what I claim, and desire to secure by Letters Patent, is—

1. A fire-box lining having its body provided 60 at its center with a series of transversely-arranged V-shaped corrugations adapted to receive a correspondingly-shaped ridge on the arm of each of its adjustable end wings, substantially as and for the purpose set forth. 65

2. The combination, with a fire-box lining having its body provided at its center with a series of V-shaped corrugations, of the hooks D D, substantially as described and shown, for holding the adjustable side or end wings of 70 75 such lining in proper position upon its body, as set forth.

3. In a fire-box lining, the body A, provided with the V-shaped corrugations a, hooks D D, and openings d d, substantially as described 75 and shown.

4. In a fire-box lining, the body A, provided with the depression B, its extensions B' B', and the V-shaped ridges b, substantially as described. 80

5. In a fire-box lining, the adjustable and removable wings E, having the arms F, provided with the V-shaped ridges f, substantially as described and shown.

6. In a fire-box lining, the wing C, having 8 85 the arms C', provided with the V-shaped corrugations c, substantially as described and shown.

7. The fire-box lining described, consisting 90 of the body A, having depression B and B', and hooks D D, the adjustable and removable end wings, E, and the adjustable and removable wing C, all constructed, arranged, and secured together substantially as described and shown, and for the purpose set forth. 95

This specification signed and witnessed this 26th day of June, 1882.

EDGAR E. BUNKER.
